UNITED STATES PATENT OFFICE.

ARTHUR M. SPINK, OF SAN FRANCISCO, CALIFORNIA.

MECHANISM FOR OPERATING DOORS AND OTHER HINGED CLOSURES.

No. 837,591.

Specification of Letters Patent.

Patented Dec. 4, 1906.

Application filed March 30, 1906. Serial No. 308,850.

To all whom it may concern:

Be it known that I, ARTHUR M. SPINK, a citizen of the United States, residing in the city and county of San Francisco and State of California, have invented new and useful Improvements in Mechanism for Operating Doors and other Hinged Closures, of which the following is a specification.

My invention relates to improvements in means for opening and closing doors, transoms, and the like, and pertains especially to such mechanisms as are operated by hydraulic or other fluid pressure means.

My object is particularly to provide means for opening and closing a plurality of closures from one point and by means of a single operating device or actuator and, conversely, to provide means for opening and closing a single door from any one of a number of points and by any one of a number of operating machines or actuators. These means meet, first, the need or desire at times of controlling a number of doors or a number of ventilators in the simplest and most economical manner possible, and, secondly, the inconvenience in three and four story dwellings of having frequently to descend or ascend one or more flights of stairs in order to open the front door.

My further object is to provide a simple, cheap, practical, fluid-controlled engine which will not leak and which is easy to install and easy to operate.

The invention consists of the parts and the construction and combination of parts, as hereinafter more fully described and claimed, having reference to the accompanying drawings, in which—

Figure 1 is a longitudinal sectional view of my improved door opening and closing device or engine. Fig. 2 is a detail in partial section of the closing-arm. Fig. 3 is a diagrammatic view of the invention applied to operate from a plurality of floors or levels on a plurality of closures. Fig. 4 is a diagrammatic representation of the invention arranged in battery or switchboard form for operating a plurality of hinged closures from one point by a single actuating-machine.

As shown in Fig. 1, each machine comprises a cylinder A, having a head 2 at one end and a combined crank-case and head 3 at the other. 4 is a pipe entering head 2, and 5 is a pipe entering head 3, said pipes connecting with opposite ends of a corresponding machine placed at any suitable or con-

venient point. There are always at least two machines, one of which is the operating-machine or "actuator," as I call it, and the other the controlled machine. A piston 6 60 operates in cylinder A and connects by a pitman 7 with a crank 8 on shaft 9, suitably journaled and packed in boxes in the crank-case 3. The chambers on opposite sides of the piston are connected by an equalizing- 65 pipe 10, in which is a valve 11.

The "operating-machine" has a crank 12, as in Figs. 3, 4, fixed rigidly to its shaft 9. The controlled machine, or the one which connects with the door or transom, carries an 70 arm 13, rigid on its shaft 9. A link 14 pivotally connects arm 13 with the closure, so as to close or open the latter when the piston in the controlled machine is moved to rock arm 13 correspondingly. With heavy closures it 75 is desirable to prevent their slamming, as they are liable to do when closed suddenly. Consequently I employ a fluid-pressure detent or retarding device, which may be applied where needed. As shown in Fig. 2, the 80 link 14 is pivoted to one end of a cylinder 16, in which is a piston 17, having a piston-rod 18. The outer end of the piston-rod is pivoted to the outer end of the arm 13. The piston has two ports 19 20—one large and 85 one small—which connect the spaces on the two sides of the piston. The larger port 19 is valved, as at 21, and on the opposite side of the piston is a spring 22, which operates against the piston to press the latter nor- 90 mally away from the end of the cylinder which is adjacent to arm 13. The cylinder 16, like cylinder A, is to be filled with oil or other suitable liquid. The straightening movement of the link with respect to 95 arm 13 is limited by a suitable stop 23, and the parts are so arranged with reference to the door or other closure to be operated that the link and arm will engage at stop 23 and coöperate with one another as a single rigid member to open the door posi- 100 tively when arm 13 is rocked in one direction, as indicated by the arrow, Fig. 2. When the arm is rocked in the other direction to close the door, (if the arm is moved rapidly or the 105 door is heavy,) the tendency is for the arm and link to pivot on one another and for the fluid on the spring side of piston 17 to open valve 21 and rush through ports 19 20 and for the piston to compress spring 22. The 110 spring is stiff enough, however, so that while it will give to relieve shock on the appara-

tus and prevent breakage it will gradually effect the closing of the door, while the liquid flows back through the small port 19. I thus provide means for a rapid movement 5 of the piston in one direction to relieve shock and a slow movement in the other direction.

In Fig. 3 is shown a practical application of the system for operating a door 15 and a transom 24 from two floors or landings. *a* 10 represents the controlled machine for the door; *b*, the controlled machine for the transom; *c*, a first-floor operating-machine, and *d* a second-floor operating-machine. The several machines are shown in position to 15 close the door. The transom is shown as open. The opposite ends of the transom-controller *b* are connected by pipes 4' 5' with machine *c* in such fashion that the same operation of machine *c* which would open door 20 15 would act to close the transom, and vice versa. In order to cut out the door-operating machine *a* temporarily from the system to permit the independent actuation of the transom, I employ a three-way cock 25, 25 which is suitably positioned in the fluid connections between the operating-machine and the controlled machines to produce the desired results. Having opened the transom, it is held open by turning the cock again to 30 cut off circulation through the machine *b*, at the same time opening up circulation again through the machine *a*. In order that machine *d* may not be worked when machine *c* is operated, and vice versa, the pipes 4^a 5^a 35 are crossed and the pistons in the respective machines *c* *d* are so positioned that with the door closed the latter may be opened by machine *d*, and the pressure created in *d* will be transmitted through 5^a to one end of *c*; but 40 the piston in *c* is already at the limit of its stroke at the opposite end of *c*, and hence does not move. From *c* the pressure passes through pipe 5 to *a* to move the piston in the latter.

45 In Fig. 4 I have shown a single operating-machine or actuator *e* controlling a battery of machines, as *f g h i*, each of which latter controls a separate transom. In this case 26 represents a box or switchboard having two 50 pipes 4 5 connected with opposite ends of the machine *e*. The latter has an operating-crank 12, and the ends of the machine are connected around its piston by an equalizing-pipe 10, having a normally closed spring-actuated valve 11. Pipes 4 5 are connected by 55 respective pipes 5' 4' with opposite ends of each machine *f g h i*. Pipes 5' are provided with cocks 27, so that any one or more of the machines *f g h i* may be cut out and its piston 60 held stationary.

In operation, suppose all the transoms are closed and it is desired to open the one which is controlled by machine *f*, the cocks 27 for machines *g h i* are all closed and the crank 12 65 operated to cause a proper circulation of fluid

through machines *e f*. Since the machines are all of limited fluid capacity, it would be impossible ordinarily to make one machine operate all the transom-machines at once, and hence it is that the valves 27 and 11 are provided. Having opened the first transom, the second or any other may be opened by shutting off circulation through machine *f* by its cock 27, opening cock 11 to allow the piston in *e* to move back through the fluid in *e*, closing cock 11, which is automatically done by the spring 28, and then opening another cock 27 and actuating lever 12 in the proper manner, the action being repeated for each transom. To close the transoms, the same operations practically are repeated.

Having thus described my invention, what I claim, and desire to secure by Letters Patent, is—

1. In a door-closer, the combination with 85 a hinged closure, of an engine comprising a cylinder having a crank-case at one end, said cylinder and crank-case closed to form a fluid-chamber, a piston in the cylinder, a crank in the crank-case, a shaft connected 90 with the crank and extending outside the case, an arm on the shaft outside the case, operative connections between the arm and closure to open and close the latter on the reciprocation of the piston, a valved equalizing-pipe connecting the opposite ends of the cylinder, the valve in said pipe being normally 95 closed, and a second and similar fluid-engine for operating the first one, and having suitable fluid connections between its ends 100 and the corresponding ends of the first engine.

2. In a door closer and opener, a hinged closure, a fluid-pressure cylinder, a piston in 105 said cylinder, a crank-shaft operatively connected for oscillation with said piston, fluid-actuated means to operate the piston, an arm rigid on said shaft, a link pivoted to said arm and to said closure and a retarding device in the connections between the link and arm.

3. In a door closer and opener, a hinged closure, a fluid-pressure cylinder, a piston in 115 said cylinder, a crank-shaft operatively connected for oscillation with said piston, fluid-actuated means to operate the piston, an arm rigid on said shaft, a link pivoted to said arm and to said closure, a retarding device in the connections between the link and arm, and means permitting an accelerated movement 120 of the arm in one direction.

4. In a door closer and opener, a hinged closure, a fluid-pressure cylinder, a piston in 125 said cylinder, a crank-shaft operatively connected for oscillation with said piston, fluid-actuated means to operate the piston, an arm rigid on said shaft, a link pivoted to said arm and to said closure, a retarding device in the connections between the link and arm, said retarding device including a cylinder pivoted 130

to the link, a ported piston in the cylinder, and a spring-actuated piston-rod connected with the arm.

5. The combination with a door of an operating-machine for the door, a plurality of actuators in series for operating the operating-machine and means to permit each actuator to operate independently to open the door.

10. 6. The combination of a plurality of movable closures, a plurality of fluid-pressure-controlled mechanisms for operating said

closures, a plurality of fluid-pressure-operated actuators having suitable fluid connections with said closure-operating mechanisms, and means by which any particular closure may be operated by any particular actuator.

In testimony whereof I have hereunto set my hand in presence of two subscribing witnesses.
